UNITED STATES PATENT OFFICE.

FRED WILLIAM MEYER, OF LOUISVILLE, KENTUCKY.

STOP AND WASTE BOX.

1,158,528.

Specification of Letters Patent.

Patented Nov. 2, 1915.

Application filed August 22, 1914. Serial No. 858,061.

To all whom it may concern:

Be it known that I, FRED W. MEYER, a citizen of the United States, residing at Louisville, in the county of Jefferson and State of Kentucky, have invented certain new and useful Improvements in Stop and Waste Boxes; and I hereby declare that the following is a full, clear, and exact description thereof, reference being had to the accompanying drawings, which form part of this specification.

This invention is a novel improvement in stop boxes or valves and stop and waste boxes and is particularly designed for use in connection with outside water pipes such as are used for hydrants and for hose connections; and the object of the invention is to provide an improved and simple construction whereby the flow of water may be effectively controlled, and when the water is cut off any water remaining in the box is permitted to escape, and also any water remaining in the pipes beyond the box can be permitted to escape, thus preventing injury to the valves or box by freezing of water standing in the pipes. And also for use with street cut-off valves controlling the connection of house pipes with the water main. I will explain the invention with reference to the accompanying drawings in which:—

Figure 1 is a vertical sectional elevation of the complete device. Fig. 2 is a transverse section on the line 2—2, Fig. 1. Fig. 3 is a detail section on line 3—3, Fig. 1.

In the drawings 1^a designates a tubular casing the lower end of which is connected to a T-shaped casting 2, the shank or stem 2^b of which is tubular and extends vertically upward and is divided by a partition 2^a into two vertical passages 2^x and 2^y which are separated by said partition. The lower end of this casting 2 has oppositely projecting tubular extensions or nipples 2^b and 2^c; and it may also have above these nipples an annular flange 2^e internally threaded for the engagement of the casing 1^a as shown; the passage 2^x connects with the nipple 2^b and the passage 2^y with the nipple 2^c. Inclosing the lower part of the casting 2 is a sand box 1, which may be detachably secured to the casting 2 by means of shoe-clamps 1^a and 1^b, the upper ends of which are slipped over the nipples 2^b and 2^c while their lower ends are hooked under the box 1 in the usual manner. The shoe-clamps are secured in position on

the nipples by means of couplings 3 and 3^b by which couplings the inlet and outlet pipes 3^a and 3^c are connected to the casting 2. The pipe 3^a may lead to a water main or supply, while the pipe 3^c leads to any desirable point of distribution.

The casting 2 is provided with an annular flange 2^e surrounding its shank, and above the nipples 2^b, 2^c, which flange is internally threaded and engaged by the lower end of the tubular casing 1^a of the box. Said casing is similarly connected at top to an annular flange 1^e depending from the top member 1^g of the box.

Slidably fitted upon and around the shank 2^b of the casting is an annulus 4 which is preferably made to closely fit the said shank and is slidable longitudinally thereof. And this annulus 4 is screwed into the lower end of a cup-shaped member 4^a which surrounds the upper end of the shank. A water-tight connection may be made between the member 4^a and the exterior of the shank 2^b by the annulus 4 and any suitable packing as indicated at 4^b in the drawings so that water cannot escape exteriorly from the cup 4^a when the valve is open. Within the cup is a valve which may consist of a disk 6 which may be of any suitable material adapted to make a close water-tight joint between the cup-member, and the upper end of the shank 2^b of casting 2, so as to positively close passage 2^x and prevent communication between the upper end of such passage and the upper end of the passage 2^a while the cup-member is lowered as shown in Fig. 1, thus cutting off the supply of water to the pipe 3^c. The disk 6 may be removably secured in the member 4^a by means of a pin or screw 6^b extending through a central opening in the washer and tapped into the member 4^a as shown.

The cup-member 4^a is connected in any suitable manner to the lower end of a valve rod or tube 4^c, the upper end of which is connected to a bifurcated clutch member 4^d which engages a flange 5^a on the lower end of a valve operating screw 5, which is tapped through the bottom of the box 1^e and through a threaded flange 5^e formed on a plate 5^f which may be secured in the top portion 1^g by means of a bolt 5^g, as indicated in Fig. 1. By turning the screw 5, by means of a suitable wrench or key, the rod 4^c can be raised or lowered so as to raise or lower the cup 4^a and open or close the valve 6.

In the shank 2^s near the upper end of passage 2^a is an opening 2^h through which water can pass from the inside of the cup into said passage 2^a, or vice versa. In the outer wall 5 of the shank 2^s adjacent the chamber 2^a is a groove 2ⁱ which extends from a point below the lowermost point assumed by the annulus 4 to a point slightly above the top of this annulus when the valve is closed, for a purpose 10 post hereinafter explained. When the screw 5 is turned so as to forcibly depress rod 4^e the top of the cup forcibly seats valve 6 upon the top of the shank 2 and prevents escape of water from the passage 2^a and into the passage 2^s. The part 1^g may be made in 15 the form of a box so as to inclose screw 5 and plate 5^f, and may be closed by a cover 1^m in the usual manner.

Operation:—When the parts are assembled as shown in Fig. 1, if the cup 4^a be raised the valve 6 will be opened and allow water to pass up through the passage 2^s into the cup and thence through the passage 2^a to pipe 3^e. When screw 5 is turned so as to 20 depress cup 4^a, valve 6 will be seated on the shank 2^s and close passage 2^a and cut off the flow of water. In the lowest position of the cup the upper end of the passage 2^a of the drain groove 2ⁱ is in communication with the 25 interior of the cup and permits water which has been trapped in the cup 4^a to drain into the casing and escape into the sand cup and out through an opening 1^p in the bottom thereof. Any water in the pipes connected 30 with nipple 2^c and above the level of the opening 2^h can escape through said opening into the cup and thence through the drain groove 2ⁱ into the casing out at the passage 1^p when the valve is closed.

40 What I claim is:

1. A stop and waste box comprising a casting having vertical passages in its shank and inlet and outlet nipples communicating therewith at its lower end, a cup-shaped 45 member telescoping the shank of the casting and adapted to close the end of one of the passages in said casting; a gasket forming a slideable closed connection between the lower end of said cup and exterior of the shank, said shank having a passage extending 50 from a point outside of the cup to a point inside thereof when the cup is in its lowermost position, to permit drainage from the cup when the valve is closed; a casing to which the casting is attached, a top box connected to said casing, a valve operating member in said box, a connection between said valve operating member and said cup-shaped member; a sand box beneath the casting, and shoes attaching the box to said casting, substantially as described.

2. In combination, a casting having parallel inlet and outlet passages in its shank and inlet and outlet nipples communicating therewith at its lower end, a cup-shaped 60

member telescoping the shank of the casting adapted to close communication between the ends of said passages, and means for operating the valve member; a gasket forming a slideable closed connection between the lower 70 end of said cup and exterior of the shank, said shank having a passage in its wall extending from a point outside of the cup to a point inside thereof when the cup is in its lowermost position to permit drainage from 75 the cup when the valve is closed; and the casting having an opening within the cup-member communicating with the outlet channel whereby water may drain back from the pipe through the cup to the outlet. 80

3. In combination, a casting having parallel inlet and outlet passages, a hollow cup-shaped member slidably telescoping the end of the casting at the adjacent ends of both 85 passages and movable longitudinally of the passages to simultaneously cover the adjacent ends of both passages to close communication therebetween or to simultaneously uncover their ends and establish communication through its interior between the adjacent ends of said passages. 90

4. In combination, a casting having parallel inlet and outlet passages, a hollow cup-shaped member slidably telescoping the end of the casting at the adjacent ends of both 95 passages and movable longitudinally of the passages to simultaneously cover the adjacent ends of both passages to close communication therebetween or to simultaneously uncover their ends and establish communication through its interior between the adjacent ends of said passages; said casting also 100 having a drain passage beside the other passages and extending from a point outside the cup-shaped member to a point inside thereof when the latter is in its lowermost position.

5. In combination, a casting having parallel inlet and outlet passages, a hollow cup-shaped member slidably telescoping the end 110 of the casting at the adjacent ends of both passages and movable longitudinally of the passages to simultaneously cover the adjacent ends of both passages to close communication therebetween or to simultaneously 115 uncover their ends and establish communication through its interior between the adjacent ends of said passages; with a top box connected to said casting, a valve operating member in said box, and a connection between said valve operating member and said cup-shaped member whereby the latter may be raised or lowered to open or close the valve. 120

6. In combination, a casting having parallel inlet and outlet passages, a hollow cup-shaped member slidably telescoping the end 125 of the casting at the adjacent ends of both passages and movable longitudinally of the passages to simultaneously cover the adj- 130

cent ends of both passages to close communication therebetween or to simultaneously uncover their ends and establish communication through its interior between the adjacent ends of said passages; said casting also having a drain passage beside the other passages and extending from a point outside the cup-shaped member to a point inside thereof when the latter is in its lowermost position; with a top box connected to said casting, a valve operating member in said box, and a connection between said valve operating member and said cup-shaped member whereby the latter may be raised or lowered to open or close the valve.

7. In combination, a casting having parallel inlet and outlet passages in its shank and inlet and outlet nipples communicating therewith at its lower end, a cup-shaped member telescoping the shank of the casting, a cup-shaped valve in said member slidably mounted on the inner end of said casting and adapted to close communication between the ends of said passages; and a gasket forming a slidable closed connection between the lower end of said cup and exterior of the shank; with a casing to which the casting is attached, a top box connected to said casing, a valve operating member in said box, and a connection between said valve operating member and said cup-member whereby the said cup-member may be

raised or lowered on the stem to open or close the valve.

8. In combination, a casting having parallel inlet and outlet passages in its shank and inlet and outlet nipples communicating therewith at its lower end, a cup-shaped member slidably mounted on the inner end of said casting and telescoping the shank of the casting, a valve in said member adapted to close communication between the ends of said passages, and a gasket forming a slidable closed connection between the lower end of said cup and exterior of the shank; said shank having a third passage extending from a point outside of the cup to a point inside thereof when the cup is in its lowermost position to permit drainage from the cup when the valve is closed; with a casing to which the casting is attached, a top box connected to said casing, a valve operating member in said box, and a connection between said valve operating member and said cup-member whereby the said cup-member may be raised or lowered on the stem to open or close the valve.

In testimony that I claim the foregoing as my own, I affix my signature in presence of two witnesses.

FRED WILLIAM MEYER.
